UNITED STATES PATENT OFFICE.

WINTHROP M. CHAPMAN, OF NEEDHAM, MASSACHUSETTS.

SIGNAL-CONTROLLING APPARATUS.

Application filed February 18, 1917. Serial No. 148,312.

To all whom it may concern:

Be it known that I, WINTHROP M. CHAPMAN, a citizen of the United States, residing at Needham, in the county of Norfolk and 5 State of Massachusetts, have invented certain new and useful Improvements in Signal-Controlling Apparatus; and I do hereby declare the following to be a full, clear, and exact description of the invention, such as 10 will enable others skilled in the art to which it appertains to make and use the same.

The present invention relates to signal controlling apparatus adapted for use in connection with the block signals of an electric trolley road and more particularly to signal controlling apparatus which embody a signal controlling device in the form of a relay which when actuated closes a signal circuit and the operation of which relay 20 is in turn controlled by contacts which for convenience may be termed "rail" contacts and which include an insulated section of rail.

The object of the present invention is to 25 produce a signal controlling apparatus of the character above referred to in which an improper or unanticipated actuation of the relay will be prevented in case the relay circuit, after being closed by the wheels of 30 a car, is successively opened and closed for any reason, as for instance, the presence of dirt, leaves or other insulating material on the track.

Another object of the present invention is 35 to produce a track relay of improved construction and operation particularly adapted for use in signal controlling apparatus.

With the above objects in view the present invention consists in the combinations 40 and arrangements of parts, circuit connections and contacts hereinafter described and claimed the advantages of which will be obvious to those skilled in the art from the following description.

The preferred form of the several features of the present invention are illustrated in the accompanying drawings, in which Figure 1 is a view in side elevation of a track relay mechanism designed for 45 use in connection with block signal systems of electric trolley roads and adapted when actuated by cars passing in one direction to close one signal circuit and when actuated by cars passing in the opposite direction to close another signal circuit; Fig. 2 is a detail view of the relay armatures il-

lustrated in Fig. 1, showing the armatures in the position they assume when actuated successively by cars passing in one direction; Fig. 3 is a view similar to Fig. 2 showing the position which the armatures assume when actuated by cars passing in the opposite direction; Fig. 4 is a detail perspective view of one of the contact carrying blocks of the relay armatures; Fig. 5 is a diagrammatic view showing the circuit connections of a signal controlling apparatus using the relay illustrated in Fig. 1 and adapted to control the operation of signals for cars passing in both directions; and Fig. 6 is a 70 diagrammatic view of a signal controlling apparatus similar to that illustrated in Fig. 5 but omitting the unlocking magnet of the relay and showing a shunt circuit for shunting the gap between the two insulated rail 75 sections when the armatures of the relay are brought together.

The relay illustrated in Fig. 1 comprises opposed magnets 1 and 2 of the solenoid type provided, respectively, with armature cores 80 3 and 4 connected by links 5 and 6 to the lower arms of pivotally mounted levers 7 and 8, the arrangement being such that when the magnet 1 is energized the lever 7 is swung about its pivot to lower the upper 85 arm and when the magnet 2 is energized the lever 8 is actuated in a similar manner. The lower arms of the levers 7 and 8 are connected by a spring 9 which, while the magnets are deenergized, holds the lower arms 90 of the levers 7 and 8 against adjustable stop screws 10 and 11. The upper arm of the lever 7 carries a block 12 of insulating material and the upper arm of the lever 8 carries a similar block 13. Upon the block 95 12 are mounted contact plates 14 and 15 and upon the block 13 are mounted contact plates 16 and 17. The contact plates 15 and 16 extend upwardly in line with the upper surface of the blocks 12 and 13 while the 100 plates 14 and 17 at their upper ends are offset upwardly with relation to the upper surface of the blocks so that the upper ends of these plates are located in a different plane from the plates 15 and 16. The offset plate 105 14 is opposite the straight plate 16 and the offset plate 17 is opposite the straight plate 15, as is clearly shown in the drawings. The result of this arrangement is that when the levers 7 and 8 are actuated successively to 110 bring them into the position illustrated in Fig. 2 the contact plate 16 engages the plate

14 and when the levers are actuated successively to bring them into the position illustrated in Fig. 3 the contact plate 15 engages the plate 17. As will hereinafter be explained the contact plates 16 and 17 are connected to a common source of current and the contacts 14 and 15 are connected to different signal circuits. Accordingly when the levers 7 and 8 assume the position illustrated in Fig. 2, one signal circuit is closed and when the levers assume the position illustrated in Fig. 3, another signal circuit is closed. The backward or retracting movements of the armature cores 3 and 4 are limited by adjustable stop blocks 18 and 19 held in place by set screws 20 and 21.

Referring now to Fig. 5, a trolley wire is indicated at 22 a continuous rail at 23, and insulated rail sections at 24, 25, 26 and 27. 28 indicates a wire connecting the trolley wire with the relay contacts 16 and 17, and 29 and 30 indicate separate signal circuit wires connected, respectively, to the relay contacts 14 and 15. A local battery is indicated at 31, one pole of which is connected through the wires 32 and 33 and interposed hand switch 34 to the continuous rail 23 and the other pole of which is connected by wires 35 and 36 to one terminal of each of the relay magnets 1 and 2. The other terminals of these magnets are connected, respectively, to the insulated track sections 25 and 26. It will be obvious from an inspection of Fig. 5 that a car passing from left to right will energize the magnet 1 as soon as the front wheels of the car pass on to the insulated section 25 and that the magnet 2 will be energized as soon as the front wheels of the car reach the insulated section 26. The armatures of the magnets will thus be actuated successively and the levers connected to the armatures will assume the position indicated in Fig. 2, bringing the contacts 14 and 16 into engagement and closing the signal circuit 29. In like manner it will be obvious that when a car passes from right to left the magnet 2 will be first energized and then the magnet 1 and the levers of the relay will assume the position illustrated in Fig. 3, thereby closing the signal circuit 30.

From the foregoing description and from an inspection of Fig. 5 it will be obvious that the successive actuation of both levers of the relay is required to close a signal circuit. It will also be obvious that after both levers have been actuated and assumed, for instance, the position indicated in either Fig. 2 or Fig. 3, an interruption and subsequent closure of the relay magnet which was last energized will tend to cause a movement of its contact carrying lever sufficient to open and again close the signal circuit. Such an interruption of the relay circuit may be occasioned, for instance, by leaves or dirt 65 or other insulating material upon one of the

insulated track sections 25 and 26. To illustrate further, suppose the front wheels of a car passing from left to right be upon insulated track section 26 and the rear wheels of the car be upon insulated section 25, 70 magnets 1 and 2 having been energized successively and the contact carrying levers having taken the position indicated in Fig. 2; if now, the wheel on insulated track section 26 passes over leaves or dirt the circuits 75 of magnet 2 may be successively broken and closed, thereby tending to produce a movement of the lever 8 sufficient to break and again make signal circuit 29 at the contacts 14 and 16. To guard against an improper 80 actuation of the relay under the conditions stated above and also to prolong the closure of the signal circuit until the car has passed from the insulated track section, the contact carrying levers 7 and 8 of the relay 85 illustrated in the drawings are provided with locking devices which hold them in the positions to which they are moved in closing one or the other of the signal circuits and means for actuating these locking 90 devices to release the contact carrying levers is provided, which means includes a magnet the circuit of which is arranged to be closed by the car after it passes beyond the last insulated rail section connected to the relay 95 magnets. As illustrated in the drawings one of the locking devices consists of a link 37 pivotally connected to the lower end of lever 7 and carrying a locking pin 38. The other locking device, which cooperates with 100 the pin 38, consists of a pawl or latch 39 pivotally mounted upon the lower end of the lever 8 and acted upon by a spring 40. The link 37 is provided with a slot 41 through which passes the stud on which the latch 39 105 is mounted so that the link 37 is pivotally supported at one end by the lever 7 and slidably supported at the other end by the lever 8. The slot 41 permits a relative movement of the levers 7 and 8 and the arrangement of the pin 38 and latch 39 is such, as will be obvious from an inspection of Figs. 1, 2 and 3, that a movement of the levers to either of the positions indicated in Figs. 2 and 3 brings the locking devices into 110 engagement. To release the locking devices and permit the contact carrying levers 7 and 8 to return to the position indicated in Fig. 1 an arm 42 is arranged to extend beneath a pin 43 projecting laterally from the latch 115 120 39 so that an upward movement of the arm lifts the latch out of engagement with the pin 38. The arm 42 projects from the hub of a lever 44, the lower end of which is acted upon by a spring 45 and the upper end of 125 which is connected by a link 46 to the armature core 47 of a solenoid magnet 48. This magnet 48, as is indicated in Fig. 5, has one terminal connected to the wire 36 which leads to one pole of the battery 31 and the 130

other terminal connected to the two insulated track sections 24 and 27. With the arrangement illustrated in Fig. 5 it will be noted that the magnet 48 is energized by a car passing in either direction before the magnets 1 and 2 of the relay are energized. This, however, has no effect on the operation of the relay inasmuch as the magnet is de-energized before both magnets 1 and

2 of the relay are energized. After the magnets of the relay have been energized successively to close one of the signal circuits 29 and 30, hereinbefore described, the signal circuit is maintained closed by the locking devices until the car passes on to the other insulated track section 24 or 27 and thereby energizes the magnet 48 and causes an actuation of the locking devices to release the contact carrying levers.

In Figs. 1, 2 and 3 the blocks 12 and 13 of the contact carrying levers are shown as being provided with co-operating contacts 49 and 50. These contacts, as illustrated in Fig. 6, may be connected to the insulated rail sections 25 and 26 so as to shunt the gap between these sections as soon as the contact carrying levers are brought together into a position to close one or the other of the signal circuits. The result of this arrangement is that both magnets 1 and 2 remain energized so long as any of the wheels of the car remain upon either insulated track section 25 or 26. In other words, if the front wheels of a car are on section 26 and the rear wheels on section 25, then a series of alternate breaks and closures at the rail contact 26 will not de-energize magnet 2 of the relay and the contact carrying levers will be maintained in position to close a signal circuit until the car passes off of the insulated sections.

The track relay mechanism and the signal controlling apparatus which have been illustrated and described and which embody the several features of the present invention in their preferred form are adapted for use with cars passing in both directions. It will be obvious, however, that certain features of mechanism, apparatus and circuit connections are equally applicable for use with cars passing in one direction only and it is, therefore, to be understood that except as defined in the claims the several features of the invention are not limited to use in connection with cars passing in both directions. It is also to be understood that except as defined in the claims the invention is not limited to any specific construction or any particular arrangement of circuits and contacts.

The nature and scope of the present invention having been indicated and apparatus embodying the several features of the invention in their preferred form having been specifically described, what is claimed is:

1. A signal controlling apparatus, having

in combination, rail contacts including an insulated section of rail arranged to be closed by the wheels of a car, a signal controlling circuit closed by the closure of said contacts, a magnet in said circuit, a signal circuit closing member actuated by said magnet, and means for maintaining said member in circuit closing position during an interruption of said signal controlling circuit. 75

2. A signal controlling apparatus, having in combination, rail contacts including an insulated section of rail arranged to be closed by the wheels of a car, a signal controlling circuit closed by the closure of said contacts, a magnet in said circuit, a signal circuit closing member actuated by said magnet, a locking device to maintain said member in circuit closing position during an interruption of said signal controlling circuit, means including a releasing magnet for actuating said device to release said circuit closing member, and a circuit for said releasing magnet including contacts arranged to be closed by the car. 80 85

3. A signal controlling apparatus, having in combination, two relay magnets, means for energizing said magnets successively upon the passage of a car including two insulated rail sections arranged to be engaged successively by the car, members actuated by said magnets and cooperating to close a signal circuit, and means for maintaining said members in circuit closing position during an interruption of the circuit of one of 95 100 said rail sections.

4. A signal controlling apparatus, having in combination, two relay magnets, means for energizing said magnets successively upon the passage of a car, including two insulated rail sections arranged to be engaged successively by the car, members actuated by said magnets and co-operating to close a signal circuit, locking devices to maintain said members in circuit closing position during an interruption of the circuit of one of said rail sections, means including a releasing magnet for actuating said devices to release said circuit closing members, and a circuit for said releasing 110 115 magnet including contacts arranged to be closed by the car.

5. A track relay for signal controlling apparatus, having in combination, a magnet, a signal circuit closing member actuated by 120 said magnet, a locking device to hold said member in circuit closing position, a releasing magnet, and means actuated by said releasing magnet for actuating said locking device to release said circuit closing member. 125

6. A track relay for signal controlling apparatus, having in combination, two magnets, members actuated by said magnets and cooperating to close a signal circuit, locking devices carried by said members and 130

- cooperating to lock said members in circuit closing position, and means for actuating said locking devices to release said circuit closing members.
- 5 7. A track relay for signal controlling apparatus, having in combination, two magnets, members actuated by said magnets and movable to one position to close a signal circuit when the magnets are energized successively in one order and movable to another position to close another signal circuit when the magnets are energized in the reverse order, locking devices carried by said members and cooperating to lock said members in each of said circuit closing positions, and means for actuating said locking devices to release said circuit closing members.
8. A track relay for signal controlling apparatus, having in combination, two magnets, pivoted arms actuated by said magnets and mounted to swing toward each other, a pair of contacts projecting beyond the end of each arm, one contact of each pair being offset with relation to the other to lie in a different plane, said contacts being so arranged that the offset contact on one arm engages a contact on the other arm to close one signal circuit when the magnets are energized successively in one order and the offset contact on the other arm engages a contact on the first mentioned arm to close another signal circuit when the magnets are energized successively in the reverse order.

WINTHROP M. CHAPMAN.
